UNITED STATES PATENT OFFICE

170,301

FLUID PRESSURE OPERATED BUMPER JACK FOR AUTOMOTIVE VEHICLES

Charles E. Branick, Fargo, N. Dak.

Application July 10, 1952, Serial No. 20,555

Term of patent 14 years

(Cl. D41—1)

To all whom it may concern:

Be it known that I, Charles E. Branick, a citizen of the United States, residing at Fargo, State of North Dakota, have invented a new, original, and ornamental Design for a Fluid Pressure Operated Bumper Jack for Automotive Vehicles, of which the following is a specification, reference being had to the accompanying drawing, forming a part hereof.

Fig. 1 is a front perspective view of a fluid pressure operated bumper jack for automotive vehicles, showing my new design; and

Fig. 2 is a rear perspective view of the jack for automotive vehicles, both sides being identical.

I claim:

The ornamental design for a fluid pressure operated bumper jack for automotive vehicles, as shown and described.

CHARLES E. BRANICK.
